ELBERT R. SITTON, OF HOUSTON, TEXAS

HEAT INSULATION

Application filed October 20, 1927. Serial No. 227,369.

My present invention relates to heat insulating material and more particularly to improved means for reinforcing same and for securing the material against the surface which it is desired to insulate.

The invention will be best understood by reference to the following detailed description taken with the annexed drawings in which,

Figure 1 is a view in transverse section of an installation including an illustrative embodiment of the invention; Fig. 2 is an elevation as seen from either side of Figure 1 and having parts in section and broken away; Fig. 3 is a view similar to Fig. 2 but showing a modification; Fig. 4 is a view in front elevation showing the invention as applied to an insulating covering for an oil still or like apparatus; Fig. 5 is a view of an individual block illustrating one form thereof; Fig. 6 is a view in perspective of a reinforcing and securing rod; Fig. 7 shows an alternative form of securing means; and Figs. 8 and 9 show forms of the invention in which different means are employed for attaching the rods to the insulation.

Referring now to the drawings by characters of reference, 10 denotes a metal shell which may constitute an oil still, boiler or other heat radiating surface of considerable size to which are secured in a manner to be described blocks 11 of suitable insulating material, the exact nature of which the present invention is not concerned, except that the invention is particularly applicable to insulating material which possesses some degree of rigidity. For the purpose of securing the blocks 11 in place and for affording reinforcement for same I have in the preferred embodiment, provided rods 12 which have intermediate portions *a*—see Fig. 6.—of a shape or curvature conforming with that of the surface to be insulated and preferably lying next to such surface, and also radially extending portions *b* to embrace the sides of the block. The latter as shown in Fig. 5 is provided with recesses 13 in the sides thereof to receive the portions *b* of the rods. Finally the rods 12 have end portions *c* which preferably extend

back along or parallel to the outer surface of the block so as to firmly enclose same.

As shown, rods 12 of circumferentially adjacent blocks 11 are preferably arranged so as to be in substantial register whereby the terminal portions *c* of such adjacent rods abut one another and may easily be secured together as, for example, by means of a looped and twisted wire 14 secured beneath the portions *c*. Obviously, if desired, the ends *c* may be countersunk in the outer surface of the insulating material so as to enable such surface to be smooth.

By means of the construction thus far described, it will be readily seen that convenient and simple means have been provided for maintaining the insulation blocks in place and for reinforcing same. In addition, by virtue of the means described of connecting adjacent holding rods, a ready means of removing a given block is had, it being only necessary to remove the wires 14 along a single line of separation whereupon the block whose removal is desired may be swung backward using the connections on the opposite line of separation as hinges. This operation is shown in Fig. 4 which illustrates the insulation applied to an oil still 17. In this manner, the plates forming the shell of the boiler as, for example, those shown at 18, Fig. 4, may be readily made accessible. This is of particular advantage in the case of high pressure oil stills where the rivets and seams have to be caulked frequently because of the intense firing to which they are subjected. Furthermore, on oil-field boilers which are moved from place to place, the insulation may be wholly or partially removed as may be necessary on account of the exigencies of moving.

The number of sections employed per 360° of circumference will usually vary in accordance with the diameter of the apparatus whose surface is to be insulated, the size of larger blocks conveniently being not larger than three feet square. Thus in the case of a pipe line, for example, only two sections per 360° of circumference need as a rule be employed. Furthermore other modes of fastening may be used for the rods; thus the

ends of the latter may be flattened and provided with holes to receive a bolt which may be held in place by the usual nut, all of which is shown in Fig. 7. With reference to the 5 form of block shown in Figs. 2 and 5 the same is formed with internal grooves 20, Fig. 5, to receive the rods 12, this construction permitting the material to be disposed flush with the surface to be insulated. In 10 order to facilitate the manufacture of the blocks, I may, however, omit the grooves 20 and allow the blocks to rest upon the rods as shown in Fig. 3. In such case I preferably fill the space between the shell and the insulating material with insulating cement 22. 15 By the term "rods" I intend to include various other forms of reinforcing material suitable for the purpose, as, for example, light channel irons, metal straps, etc. 20 Furthermore, depending upon the nature of the heat insulating material, I may pass the middle or intermediate portion of the rods through the body of the blocks; ordinarily, however, this construction is not necessary, 25 it being a feature of the invention that the improved securing and reinforcing means proposed is such as to dispense with the need for internal reinforcement including the usual hardware-cloth, poultry netting, etc. 30 In Figs. 8 and 9 I have shown an alternative method of attaching the rods to the blocks by wiring the same thereto. In Fig. 8, for example, the wire 25 makes loops 26 around rod 12, the upper stretches of the wire preferably being contained within a slight groove 26a at the surface of the insulation. Wire 20 is also conveniently provided with portions 27 by means of which adjacent block sections may be secured together as by the use of 40 attaching wires 28. In Fig. 9 a similar construction is presented except that the rod 12 lies at or near the outer surface of the insulation 11. In this latter construction also the rods 12 have portions 30 forming the 45 securing means instead of the wires 25. It will be evident that the forms of the invention just described are of particular value when the insulating material is of such nature that it may be cast around the reinforcing 50 structure, and where the existing shapes of the material do not have to be utilized.

It will be understood that the various embodiments described are illustrative only and that various changes may be made without departing from the spirit of my invention or scope of the appended claims.

I claim:

1. A heat insulating covering comprising a plurality of blocks of insulating material 60 and reinforcing and retaining members therefor consisting of metal rods extending beneath said blocks and around the sides thereof and means joining the ends of adjacent rods serving to secure said blocks in place and insulating cement in the space be-

tween the insulated surface and said blocks occasioned by the presence of said rods.

2. A heat insulating covering comprising blocks of heat insulating material and reinforcing rods passing beneath the surface of the blocks and having exteriorly extending portions binding the sides of said blocks and means securing rods of adjacent blocks constituting hinges therefor. 70

3. A heat insulating covering comprising blocks of heat insulating material of substantially rigid but friable nature and reinforcing and retaining rods therefor extending beneath said blocks said rods being individual to said blocks and removable therewith, and means for securing said rods to said blocks comprising a wire having loops extending from the exterior portion of the block and engaging said rods. 80

4. A heat insulating covering comprising removable abutting sections of substantially rigid but friable heat insulating material, re-inforcing and retaining metal rods individual to said blocks and extending beneath the outer surface thereof and substantially around three dimensions thereof, said rods being removable with the sections around which they extend and serving to protect said sections both in and out of service. 85 90

5. A heat insulating covering comprising removable abutting sections of substantially rigid but friable heat insulating material, re-inforcing and retaining metal rods individual to said blocks and extending around three dimensions thereof and having their ends engaging a fourth side, said rods being removable with said sections and serving to protect same both in and out of service. 95 100

6. A heat insulating covering comprising removable abutting sections of substantially rigid but friable heat insulating material, re-inforcing and retaining metal rods individual to said blocks and extending beneath the outer surface thereof and substantially around three dimensions thereof, said rods being removable with the sections around which they extend and serving to protect said sections both in and out of service, and tie means engaging said rods for securing adjacent sections together. 105 110 115

In testimony whereof I have affixed my signature to this specification.

ELBERT R. SITTON.
